NEUTRALIZING SYSTEM

James W. Conklin, Audubon, N. J., assignor to
Radio Corporation of America, a corporation of
Delaware

Application March 31, 1939, Serial No. 265,235

4 Claims. (Cl. 179—171)

This invention relates to neutralizing systems. Its primary purpose is to provide an improved mechanical arrangement for neutralizing radio frequency amplifiers, and has a particular application to ultra high frequency amplifiers of the parallel conductor tank circuit type.

The use of neutralizing capacitors to prevent oscillation in a single or push-pull amplifier is well known to those skilled in the art. In attempting to carry out the application of neutralizing capacitors to ultra high frequency circuits, several considerations became of importance if a stable arrangement is to be obtained. It is necessary to provide means for adjusting the neutralizing capacitors while the transmitter is in operation for the sake of convenience and to obtain the best possible adjustment. At the same time, it is necessary to avoid an arrangement in which the adjusting medium interferes with or disturbs the normal radio frequency field in the vicinity of the neutralizing capacitors. Since the field is usually at a maximum at the point of neutralization, the circuit is quite sensitive to changes, so that the capacity of the hand or adjusting tools frequently makes complete neutralization quite difficult.

Since neutralizing capacitors are connected to the anode circuit, one plate is at a high positive direct current potential as well as at a high radio frequency potential. Suitable precautions must, therefore, be made to prevent danger to the operator when the neutralizing adjustment is being made. At ultra high frequencies, it is known that the current through the neutralizing capacitors may be twenty or thirty amperes, so that it is advisable to eliminate sliding contacts which frequently are a source of trouble where high currents are involved, and to provide a system in which direct contacts are provided between all of the circuits.

In accordance with this invention, an arrangement is provided in which the movable plates of the neutralizing capacitors are adjustably mounted on the tank circuit inductor and provision is made for pivotally rotating the entire tank circuit through a small arc to provide the necessary neutralizing adjustment.

This invention will be better understood from the following description when considered in connection with the accompanying drawing which illustrates a preferred embodiment of this invention.

Referring to the figure of the drawing, a half-wave parallel conductor tank circuit 1 constitutes the plate impedance of a push-pull amplifier

which includes a pair of tubes 3 and 5. Since the electrical connections are conventional, it is not necessary to illustrate the entire amplifier circuit in detail. The fundamental frequency of the tank circuit conductor is adjustable by means of a sliding bar 7 which short circuits the two conductors 9 and 11 to adjust their length to the desired frequency. The lower extremity of the tank circuit 1 is mounted on and supported by a resilient spring 13, which, in turn, is supported by two stand-off insulators 17, 17.

The upper, or high potential, end of the tank circuit is supported by a pair of porcelain insulators 19 and 21 which are firmly connected by a terminal block 23. A threaded thumb screw 25 extends through a shielding enclosure 27 of the amplifier compartment. The thumb screw is provided with a pair of shoulders 24, 26 which prevents its longitudinal movement through the shield 27, but allow it to freely rotate therein. The free end of the thumb screw is threaded into the terminal block 23.

A pair of neutralizing condensers are provided at the high radio frequency potential end of the tank circuit 1. The neutralizing capacitors comprise fixed plates 29, 31 which are fixedly mounted on an insulator 37 which is supported by the compartment shield 28 and movable plates 33, 35 which are, respectively, mounted on and connected to the open ends of the tank circuit conductors 9 and 11.

In order to provide a coarse adjustment for the neutralizing capacitors, the movable plates 33 and 35 are preferably attached to the tank circuit conductors by threaded rods 39, 41, which are provided with lock nuts to insure a tight electrical connection.

Suitable connecting leads are utilized to complete the electrical circuit to the respective grid and anode electrodes of the amplifier tubes. To allow unrestricted motion for the adjustment of the neutralizing capacitors, the anode leads are preferably flexible. Input and output connections are made at coupling coils 43, 45 which are coupled, respectively, to the grid tank coil 47 and the anode tank 1.

From a consideration of the drawing, it is apparent that the neutralizing operation may be effected without danger to the operator and with complete freedom from disturbance by turning the thumb screw 25. The entire tank circuit is moved through a small angle to increase or decrease the spacing between the plates of the neutralizing capacitors. Sliding contacts have been eliminated. This accordingly increases the sta-

bility of the arrangement, particularly at ultra high frequencies. Complicated mechanical drive arrangements which have heretofore been connected to the movable plates of the neutralizing capacitors have been eliminated. Inasmuch as an insulating support is necessary to hold the tank circuit in position regardless of the arrangement which may be used to adjust the neutralizing capacitors, it is apparent that the proposed system does not increase the material required, but in fact eliminates certain parts which have heretofore been deemed necessary.

While I have illustrated my invention by means of a push-pull radio frequency amplifier, it is evident that this idea may likewise be applied to a single stage neutralizing amplifier or to the vernier adjustment of the frequency of radio frequency oscillators or the like.

I claim as my invention:

- 20 1. A neutralized radio frequency amplifier which includes a pair of neutralizing capacitors, an inductor, flexible mounting means for supporting said inductor at a point of minimum voltage, one plate of each capacitor being mounted on and connected to said inductor, and adjusting means for varying the position of the free end of said inductor to thereby vary the capacity of said capacitors.
- 25 2. A neutralized radio frequency amplifier which includes a pair of neutralizing capacitors, a parallel conductor tank circuit inductor, flexible mounting means for supporting said inductor

at a point of minimum voltage, one plate of each capacitor being mounted on said inductor, and means for varying the position of the free end of said inductor to thereby vary the capacity of said capacitors.

3. A neutralized radio frequency amplifier which includes a pair of neutralizing capacitors, a parallel conductor tank circuit closed at one end and open at the other, resilient means for mounting said inductor at said closed end, adjustable means for positioning the open end of said inductor, and a pair of neutralizing capacitors including fixed and movable plates, said movable plates being adjustably mounted on respective conductors of said inductor whereby the capacity of said neutralizing capacitors is varied by said adjustable means.

4. A neutralized radio frequency amplifier which includes a pair of neutralizing capacitors, a folded half-wave parallel conductor tank circuit closed at one end and open at the other, means for pivotally mounting said inductor at said closed end, adjustable means remote from the radio frequency field of said inductor for positioning the open end of said inductor, and a pair of neutralizing capacitors including fixed and movable plates, one of said movable plates being adjustably mounted on each of said conductors whereby the capacity of said neutralizing capacitors may be varied by said adjustable means.

JAMES W. CONKLIN.
